NONICING CARBURETOR

Morris C. Brown, Brentwood, Mo., assignor to Carter Carburetor Corporation, St. Louis, Mo., a corporation of Delaware

Application March 27, 1943, Serial No. 480,805

1 Claim. (Cl. 261—41)

This invention relates to carburetors for internal combustion engines and consists particularly in novel means for preventing icing at the throttle valve, particularly during idling.

When a carburetor is idled in cold weather and before the engine heat has reached normal, the moisture content of the air drawn through the carburetor frequently condenses and freezes adjacent and on the upper surface and edges of the throttle because of the cooling effect due to expansion of the fuel and air upon passing the throttle. The ice thus formed may clog the idling port and cause the engine to stall. Various schemes for quickly heating the carburetor barrel adjacent the throttle excessively complicate the carburetor and are not wholly satisfactory.

The main object of the present invention is to provide simple, effective means for preventing icing at the throttle during idling.

This object and other more detailed objects hereafter appearing are attained by the structure illustrated in the accompanying drawing in which

Fig. 1 is a side view, mostly sectioned, illustrating an automotive carburetor and portion of an associated intake manifold.

Fig. 2 is a side view of the idle stop mechanism.

The carburetor shown comprises a downdraft mixture barrel including an air inlet horn 5, mixing conduit 6 including venturi 7, and an outlet portion 8 controlled by a butterfly throttle valve 9 pivotally mounted on a shaft 10. A choker valve 11 is pivotally mounted in the air horn and controlled by any suitable manual or automatic means. The carburetor is mounted on the riser portion 12 of the intake manifold 13 and above the usual hot spot 14.

Adjacent the barrel is a fuel bowl 18 within which fuel is maintained at a substantially constant level by the usual needle valve mechanism (not shown) controlled by a float 19. Fuel is supplied to the mixing conduit through a metering orifice 20, controlled by a metering pin 21, and a main fuel passage 22 terminating in a fuel nozzle 23 which opens into the smallest venturi 7. Metering rod 21 is controlled by the throttle by means of a lever 24, a link 25 and an arm 26 rigid with throttle shaft 10. Fuel for idling is supplied through passages 30 and 31 terminating in idling ports 32 and 33. Port 32 opens on both sides of throttle plate 9 when closed and port 33 is provided with an adjusting screw 34.

On the end of throttle shaft 11, opposite arm 26, there is provided a second arm or crank 36 for connection to the usual throttle control linkage, shown in part at 37, the usual

throttle return spring, being provided, as diagrammatically indicated at 38. An adjusting screw 39 mounted in crank 36 is disposed to engage an abutment 40 on the carburetor barrel for limiting the clockwise movement of the throttle. Screw 39 is arranged to permit the throttle plate to tightly close during normal idling, but without jamming. A lip 42, bent inwardly from crank 36, provides a permanent positive stop to prevent wedging and damaging of the throttle plate. If desired screw 39 may be eliminated. An air by-pass 43 is provided around the throttle plate for supplying air, when the throttle is closed, to form a combustible idling mixture with the fuel emitting from ports 32 and 33. The quantity of air by-passed may be adjusted by a valve screw 44, the screws 34 and 44 providing for adjustment of the speed and richness of the idling mixture.

The structure operates as follows:

During normal idling when the throttle plate is tightly closed, a very rich mixture of fuel emerges from ports 32 and 33 and the air passing through by-pass 43 readily mixes with this fuel, because of the high suction posterior to the throttle, to form a properly combustible idling mixture. In present carburetors, this extra air for idling is supplied around the edge of the throttle valve which is held slightly open during normal idling. Such air, upon passing around the throttle, naturally expands and the moisture content thereof may condense and freeze. However, no such condensation and freezing can occur in the improved structure shown since practically all of the idling air emerges into the mixture conduit at a point substantially spaced from the idling ports and the throttle plate where ice crystals may be harmlessly carried to the cylinders. A slight amount of air may pass through port 32, but the moisture content in such a small quantity of air is insufficient to cause any substantial icing.

Various features of the carburetor may be modified within the knowledge of the art and the specific arrangement of the air by-pass may be varied just so long as the idling air is kept away from the idling port. The exclusive use of all modifications as come within the scope of the appended claim is contemplated.

I claim:

A non-icing carburetor comprising a mixture conduit having a throttle therein, interconnected main and idling fuel passages discharging, respectively, anterior and posterior to said throttle when closed, means to move said throttle to such

a fully closed position as to prevent a substantial air flow for normal idling through said mixture conduit, fixed stop means limiting closing of said throttle to a position to prevent jamming of said throttle against the conduit wall, a constantly open air by-pass extending around said throttle between portions of said mixture conduit spaced substantially on opposite sides of said

throttle, the discharge end of said by-pass being at a point in said conduit substantially diametrically opposite to the normal idle orifice for providing a combustible mixture during normal idling with the fuel from said idling passage, and means to vary the effective size of said by-pass to adjust the idling speed of the engine.
